2 SHEETS—SHEET 2.

UNITED STATES PATENT OFFICE.

SALVATORE PERLA, OF NEW YORK, N. Y.

AUTOMATIC MUSICAL INSTRUMENT.

1,252,835.

Specification of Letters Patent.

Patented Jan. 8, 1918.

Application filed December 13, 1916. Serial No. 136,610.

To all whom it may concern:

Be it known that I, SALVATORE PERLA, a citizen of Italy, residing at New York, N. Y., have invented a new and useful Automatic 5 Musical Instrument, of which the following is a specification.

My invention relates particularly to instruments of the player piano type and the primary objects of the invention are to combine with an instrument of this character a phonograph or so-called talking machine and to accomplish this union without sacrificing or detracting from the qualities of the 10 respective devices. This invention I have 15 called a "Pianophono."

Another object is to so build the phonograph mechanism into the player piano as not to mar the appearance of the instrument and at the same time so as to secure the 20 proper resonance, etc.

Other objects of the invention are to provide for the automatic starting and stopping of the phonograph in proper time with the player mechanism.

The invention therefore comprises in a 25 general way phonograph mechanism combined with player piano mechanism in such a way that the two will operate properly in unison, and involves novel features in the 30 construction, method of control, etc., all of which will appear as the specification proceeds, attention being now directed to the accompanying drawings wherein I have 35 illustrated the invention embodied in a practical operative form.

In these drawings:

Figure 1, is a front view with parts broken away of an embodiment of the invention illustrating a method of mounting the same 40 within the case of a player piano.

Fig. 2, is a top plan view of the same.

Fig. 3, is a partial plan and sectional view of the driving mechanism taken substantially on the plane of the line 3—3 of Fig. 1.

Fig. 4, is a cross sectional view of the same taken substantially on the plane of the line 4—4 of Fig. 3.

Fig. 5 is a longitudinal sectional view of the valve chest.

Fig. 6, is a cross-sectional view of the same taken substantially on the plane of the line 6—6 of Fig. 2.

Fig. 7, is a combined view showing two different sides of the so-called starting pneumatic.

Fig. 8, is a side view of the so-called stopping pneumatic.

Referring to the drawings now in detail:

10 designates the case of the instrument which houses the various mechanisms and 60 which may be in the form of the usual player piano case.

11 designates a tracker board, 12 a take-up spool or reel, 13 a record sheet and 14 a motor whose power shaft 15 is coupled with 65 the take-up reel, this mechanism being common to the usual player piano.

Built into and combined with the player mechanism of my invention is a phonograph 70 or talking apparatus comprising, in the present disclosure, a turntable 16 for supporting the record disks 17 and a reproducer 18 mounted on and carried by an arm 19 pivoted to rock and swing on a pivot stud 20 and supporting a horn or other suitable 75 amplifying device 21.

The phonograph is operated, in the present disclosure, from the take-up reel by a system of gearing comprising a gear 22 on the extended shaft 23 of the reel, which gear 80 meshes with gear 24 on a shaft 25, said gear 24 carrying a larger gear 26 which meshes with a gear 27 on the shaft 28, said shaft 28 carrying a bevel pinion 29 meshing with a bevel pinion 30 on the turn table shaft 31. 85 By these means the turntable is rotated from the record winding mechanism and in direct synchronism therewith, the gearing being proportioned to give the proper speed of rotation to the turntable. 90

A governor is provided for the phonograph mechanism, in the illustration, in the form of a ball governor 32 on the shaft 33 which is driven from shaft 28 by gears 34, 35, 36 and 37, the disk of said ball governor 95 being acted upon by a friction brake 38. This brake is shown in the form of an angle lever acted upon by a spring 38', pivoted at 39 and having an angular arm 40 engaging one end of the lever 41 which is pivoted at 42 and whose opposite end is positioned by means of a thumb screw or other suitable device 43, a suitable pointer and scale arrangement 44 being usually provided.

The phonograph may be coupled and uncoupled with respect to the record feeding mechanism by means comprising, in the present case, a shifting fork 45 pivoted at 46 and engaging with the gear 27 which is slidably splined on the shaft 28 so that it may 110

be shifted into and out of mesh with the companion gear 26, said shifting lever being conveniently operated by a push rod connection 47.

5 The phonograph is started in synchronism with the player by means controlled by the record sheet of the player, said means comprising a pneumatic 48 whose movable side 49 carries an arm 50 which serves as a rest 10 or support for the reproducer arm. This starting pneumatic is placed under the control of the record sheet by the provision of an extra or "starting" duct 51 in the edge portion of the tracker, the record sheet having 15 a starting perforation 52 in the edge thereof for registry with this duct, said starting duct being connected with the pneumatic 48 by air tubes 52-53, a valve chest 54 being interposed in said air connections to provide 20 the proper action.

25 In similar fashion the stopping of the phonograph is automatically controlled at the same time by an automatic "stopping" pneumatic 55 provided with a lug 56 arranged to overstand an arm or lug 57 on the rearward end of the movable reproducer element when said element has swung through the arc necessary in the playing of the record, as will be clear from Fig. 2. This stopping pneumatic is likewise controlled by a special extra duct 58 at the opposite end portion of the tracker, which duct is controlled by a correspondingly placed perforation 59 in the edge portion at the end of 30 the record. These control ducts as shown in Fig. 1 are special ducts provided in addition to the usual ducts 60 which control the player pneumatics. The stopping duct 58 is connected with the stopping pneumatic by 35 air connections 61-62 which also pass through the valve chest 54.

40 The construction of the valve chest will best be understood from Figs. 2, 5 and 6. This chest has within it a suction chamber 45 63 and diaphragm valves 64 and 65 for controlling the starting and stopping pneumatics respectively. These valves are actuated by diaphragms 66, the stem portions 67 of the valves resting directly on said diaphragms. 50 Beneath the diaphragms are chambers 68 into which the tubes 52-61 from the tracker board ducts are led.

55 The suction pipes 53-62 which lead to the pneumatics are connected with chambers 69 above the valves 64 and 65 as indicated in Fig. 6, said chambers being open to atmosphere at the top at 70 and being in communication with the suction chamber, when the valve is lifted by way of passages 71.

60 Suction is applied to the chamber 63 by a suction pipe 72 connected with the suction providing apparatus of the player by suitable piping 73. Relatively small relief or 65 bleed passages 74 establish communication

between the suction chamber 63 and the cavities 68 below the diaphragms 66.

From the foregoing it will be apparent that when the player is started and suction is applied through piping 72-73, the valves 70 will remain in the positions indicated in Figs. 5 and 6 so long as the special control ducts are covered, the pressure above and below the diaphragms being equalized through the bleed passages 74 and the weight 75 of the valves and the suction on the under sides of the same serving to maintain them in their lower position cutting off communication between the suction chamber 63 and the upper chambers 69 into which the tubes 80 53-62 are led. When however the control ducts are uncovered, for instance the starting duct 51, this will open up the space 63 beneath the diaphragm to atmosphere, the suction will lift the diaphragm, causing the 85 same to raise the valve, 64 in this case, which closes off the atmospheric passage 70 and establishes communication between the suction chamber 63 and the chamber 69 into which the tube 63 extends. A suction connection is thereupon established with the starting pneumatic and said pneumatic is collapsed thereby, the movable board of said pneumatic, thereupon lowering the reproducer support 50 and dropping the reproducer into proper starting engagement with the phonograph record.

90 To prevent interference of the support 50 with the reproducer after the reproducer has been lowered on the record the pneumatic is 100 latched in its collapsed condition by a spring latch indicated at 75 and shown provided with a perforation 76 to receive a pin 77 on the movable board of the pneumatic.

95 This starting pneumatic latch is automatically released by means of a secondary pneumatic 78 mounted on the movable portion of the starting pneumatic and whose movable board carries a pusher 79 for engagement with the spring latch 75. This 110 releasing pneumatic is operated when the end of the record is reached by means of a suction connection 80 which for the sake of simplicity, may be joined with the "stopping" suction pipe 62 as indicated in Fig. 1. 115

120 The stopping operation will also be more or less apparent from what has preceded, it being clear that when the record strip nears the end of its movement and the stopping perforation 59 therein registers with the stopping duct 58, the cavity below the diaphragm for the valve 65 will be thrown open to atmosphere and the valve 65 will be lifted as before described and suction will be applied through the tubing 62 of the 125 stopping pneumatic 55. During the playing of the phonograph record the reproducer is swung over so as to carry the lug 57 at the rear end of the same into position beneath the rearwardly extending lug 56 on the mov- 130

able board of the stopping pneumatic so that as the pneumatic is collapsed under the action of the suction thus applied the reproducer will be tilted on its pivot and lifted 5 out of engagement with the record.

Provision is made for latching such pneumatic in its collapsed condition, the means for this purpose comprising a spring latch 81 on the movable back of the pneumatic 10 provided with a perforation 82 receiving the pin 83 on the stationary back of the pneumatic.

The stopping pneumatic latch is automatically released at the proper time by 15 means, comprising in the present instance, a secondary pneumatic 84 mounted on the back of the stopping pneumatic and provided with a pusher 85 for engagement with the latch 81 to release the same from the 20 pin 83.

The releasing pneumatic of the stopping pneumatic is shown operated by a suction connection 86 which may be joined with the suction connection 53 leading to the starting 25 pneumatic.

From this cross-connection of primary and secondary pneumatics it follows that the starting pneumatic will be unlatched into reproducer supporting position when 30 the end of the record is reached and that the stopping pneumatic will be unlatched and placed into operative condition at the same time that the starting pneumatic is operated to lower the reproducer upon the record.

35 What I claim is:

1. In combination with automatic player piano mechanism, a phonograph, means for starting the phonograph at a predetermined period of the operation of the player mechanism and independently controlled means for stopping the phonograph at a predetermined period in the operation of the player mechanism.

2. In combination with automatic player 45 mechanism a phonograph including a reproducer, means for placing said reproducer in reproducing position, means for holding said placing means in one position, means for releasing said placing means, means for lifting the reproducer from reproducing position, means for holding said lifting means in one position, means for releasing said lifting means, operating means for the placing means and lifting releasing 50 means aforesaid and operating means for the lifting means and placing releasing means aforesaid.

3. In combination with a musical playing 60 instrument including a reproducer, means for placing said reproducer in reproducing position, a latch for holding said means in such placing position, means for releasing said latch, means for lifting the reproducer from reproducing position, a latch for holding 65 said lifting means in such lifting posi-

tion, means for releasing said latch, and means for operating the placing means and lifting latch releasing means aforesaid, and means for operating the lifter means and placer latch releasing means aforesaid. 70

4. In combination with automatic player mechanism, a phonograph, starting means for said phonograph, means for holding said starting means in inoperative position, separate independent means for stopping the 75 phonograph and means for operating said starting means and restoring said stopping means again to stopping position.

5. In combination with automatic player mechanism, a phonograph, stopping means 80 for said phonograph, means for holding said stopping means inoperative, separate and independent starting means for the phonograph and means for operating said starting means and restoring the stopping 85 means again to operative condition.

6. In combination with automatic player mechanism, a phonograph including a swinging reproducer element and a stopping pneumatic controlled by the player mechanism and carrying an arm disposed above the path of swinging movement of the reproducer element. 90

7. In combination with automatic player mechanism, a phonograph including a reproducer, a pneumatic controlled by the player mechanism for lifting the reproducer out of reproducing position, a latch for said pneumatic and a secondary pneumatic for releasing said latch. 95

8. In combination with automatic player mechanism, a phonograph including a reproducer, a pneumatic controlled by the player mechanism, means for lifting the reproducer operated by the collapse of said 105 pneumatic, a latch for holding the pneumatic in collapsed position and a secondary pneumatic for releasing said latch.

9. In combination with automatic player mechanism, a phonograph including a reproducer, a pneumatic controlled by the player mechanism, a support for the reproducer operated by said pneumatic, a latch for said pneumatic, a secondary pneumatic for releasing said latch, a phonograph stopping pneumatic controlled by the player mechanism, a latch for said stopping pneumatic, a secondary pneumatic for releasing said latch, air connections from the player mechanism to the starting pneumatic and to the releasing pneumatic of the stopping pneumatic and air connections from the player mechanism to the stopping pneumatic and to the releasing pneumatic of the starting pneumatic. 110

10. In combination with automatic player mechanism including a tracker board provided with additional control ducts at opposite end portions thereof and a record sheet having additional control perforations 130

in the opposite edge portions thereof for registry with said control ducts, a phonograph, a starting pneumatic for said phonograph controlled by the additional duct 5 in one end of the tracker board and a stopping pneumatic for the phonograph controlled by the other additional duct in the opposite end of the tracker board.

11. In combination with automatic player 10 mechanism, a phonograph including a reproducer, a pneumatic controlled by the player mechanism for lifting the reproducer out of reproducing position, a latch for said pneumatic, and means for releasing said 15 latch.

12. In combination with automatic player 20 mechanism, a phonograph, a starting pneumatic for said phonograph, a latch for said starting pneumatic, a stopping pneumatic for the phonograph, a latch for said stopping pneumatic, and means for controlling said latches.

13. In combination with automatic player 25 mechanism, a phonograph, a starting pneumatic for said phonograph, a latch for said starting pneumatic, a stopping pneumatic for the phonograph, a latch for said stopping pneumatic, means for simultaneously

operating the starting pneumatic and latch for the stopping pneumatic and means for 30 simultaneously operating the stopping pneumatic and the latch for the starting pneumatic.

14. In combination with automatic player mechanism, a phonograph, starting and 35 stopping pneumatics for the phonograph, latches for the starting and stopping pneumatics respectively, secondary pneumatics for operating the respective latches and air connections from the player mechanism to 40 said control pneumatics and secondary pneumatics.

15. In combination with automatic player mechanism, a phonograph, starting and stopping pneumatics for the phonograph, 45 latches for the starting and stopping pneumatics respectively, secondary pneumatics for operating the respective latches, air connections from the player mechanism to the starting pneumatic and to the secondary of 50 the stopping pneumatic and air connections from the player mechanism to the stopping pneumatic and secondary of the starting pneumatic.

SALVATORE PERLA.
